UNITED STATES PATENT OFFICE

130,360

DESIGN FOR A WOVEN FABRIC

Austin N. Oppenheim, New York, N. Y., assignor to Traub-Lyons-Oppenheim, Inc., New York,
N. Y., a corporation of New York

Application August 13, 1941, Serial No. 102,821

Term of patent 3½ years

To all whom it may concern:

Be it known that I, Austin N. Oppenheim, a citizen of the United States, residing at New York city, in the county of New York and State of New York, have invented a new, original, and ornamental Design for a Woven Fabric, of which the following is a specification, reference being had to the accompanying drawing, forming a part thereof.

The figure is a plan view of a woven fabric showing my new design.

I claim:

The ornamental design for a woven fabric, as shown.

AUSTIN N. OPPENHEIM.
